SEWING MACHINE

Norman V. Christensen, Chicago, Ill., assignor to
 Union Special Machine Company, Chicago, Ill.,
 a corporation of Illinois

Application July 25, 1938, Serial No. 221,073

9 Claims. (Cl. 112—197)

This invention relates to sewing machines. More particularly it has reference to commercial sewing machines of a type especially useful for edge seaming operations such as forming inseams and outseams of trousers, uniting the edges of fabric blanks in the manufacture of bags, and similar operations where through and through stitching is desirable. In certain of its aspects, however, the present improvements are not necessarily confined to sewing machines of the special type specifically referred to.

My invention is concerned with changes and refinements which are conducive to the attainment of higher operative efficiency in sewing machines with corresponding increase in output or production from them; and which moreover favor the attainment of greater structural compactness in such machines. These advantages I realize in practice as hereinafter more fully explained by simplifying and closely coordinating the needle actuating, the supplemental stitch-forming, and the feeding mechanisms of a sewing machine in such a way that they can all be operated from a single drive shaft and for the most part enclosed within a housing or hollow frame of small dimensions for protection against accumulation upon them of dust, lint or other clogging matter, and for the purposes of automatic lubrication with oil elevated or thrown up by splash or spray action.

Other objects and attendant advantages will appear from the following detailed description of the attached drawings, wherein Fig. I shows in longitudinal section a sewing machine conveniently embodying my invention.

Fig. II shows the machine in front elevation with the cover plate removed from the front of the needle head.

Fig. III is a staggered horizontal sectional view taken as approximately indicated by the broken dot and dash arrowed line III—III in Fig. I.

Fig. IV is a view partly in front elevation and partly in transverse section taken as indicated by the arrows IV—IV in Fig. I.

Fig. V is a staggered horizontal sectional view taken as indicated by the arrows V—V in Fig. I.

Fig. VI is a fragmentary detail sectional view indicated by the arrows VI—VI in Fig. V; and

Fig. VII is a fragmentary view in side elevation looking as indicated by the arrows VII—VII in Fig. II.

As herein illustrated, my improved sewing machine has a hollow rectangular base 1 integrally formed with longitudinal side walls 2, 3, front and rear end walls 4, 5 and a medial transverse

partition 6 with a forwardly-extending offset at 7. Rising from the base at one end in the longitudinal center of the machine is a relatively low hollow standard 8 with a rearwardly sloped back wall 9 in integral continuation with the rear end wall 5 of the base 1, a vertical front wall 10 in integral continuation with the transverse partition 6, and vertical side walls 11, 12 which are closely spaced as compared with the side walls 2, 3 of said base. The top of the base 1 is formed by a generally U-shaped horizontal work supporting plate 13 which extends beyond the side walls 2, 3 and the front end wall 4 of the base and which is secured to said walls by screws 15. From Figs. IV and V, it will be observed that the portions 2a and 4a of the walls 2 and 4 terminate short of the work supporting plate 13. As shown in Fig. I, the upper part of the standard 8 slightly overhangs the work support as at 16, said overhang constituting a guide head for the needle and presser bars of the machine which are respectively designated 17 and 18. The work supporting plate 13 fits against and is flush with a horizontal rectangular web 19 which is integral with the standard 8 and which extends forwardly and laterally respectively from the front wall 10 and the side walls 11, 12 of said standard, see Figs. I and III. Set into the work supporting plate 13 below the overhang 16 of the standard 8 is a transversely arranged throat plate 20; and located somewhat to the front of the standard is a retractable slide plate 21 whereof the longitudinal edges have suitable interlocking engagement respectively with the oppositely disposed parallel edges of a cutout 22 in the work supporting plate and of the horizontal web 19. The hollow base 1 is closed at the bottom by a plate 22 which is removably secured by screws 23 engaging upwardly into the side and end walls 2—5 and the partition 6, see Fig. I. As a consequence of this construction, there are formed at the bottom of the standard a closed chamber 25 which is kept filled with oil to the level indicated at L, and a partly closed compartment 26 for the supplemental stitch-forming and feeding mechanisms of the machine which will be presently described.

The oil in the chamber 25 may be replenished either upon withdrawing the slide 21 in the top plate 13 or upon removing a plug shown at 27 in Fig. I from an opening 28 in the rear end wall 5 of the housing.

All the moving parts of the machine are actuated from a single rotary shaft 29 which extends longitudinally through the hollow base 1 and which is journaled in ball bearings 30, 31, and 32

set into the walls 4, 5, and in the partition 6 respectively. The opening for the bearing 31 is closed by a removable plate 33 which has an internal circumferential groove 34 containing packing 35 to prevent leakage of oil from the chamber 25 past said bearing. To the protruding right hand end (Fig. I) of the shaft 29 is affixed a combined pulley and hand wheel 36 whereby the machine may be operated either under power or manually.

From Figs. I and II, it will be observed that the needle bar 17 is guided for up and down movement in a bushing 37 set into the bottom 38 of the head 16. Confined to endwise reciprocation in bearing bushings 39, 40 set into the top 41 and the bottom 38 of the overhang 16 in parallel relation to the needle bar 17 is a slide rod 42. In the interval between the bushings 39 and 40, the rod 42 carries a rotatively adjustable connecting member in the form of a bracket 43 with a laterally projecting pin 44 which telescopically engages with a sliding fit, into the transverse bore of a member 45 secured to the top end of the needle bar 17. As shown, the hub of the bracket 43 surrounds the slide rod 42 and has a set screw 43a by which said bracket can be fixed in rotatively adjusted positions. Due to the looseness of this connection, compensation is automatically made for lack of absolute parallelism between the needle bar 17 and the slide bar 42 with attendant avoidance of binding strains. This feature is highly advantageous in production in that it allows for slight variations in the spacing of the bars in different machines. At the lower end of the slide bar 42 is a clevis 46 which is pivotally engaged by the upper end of a pitman 47 whereof the lower end engages a crank 48 on the drive shaft 29.

The presser bar 18 is confined to endwise movement in bearings 49, 50 respectively at the top 40 and the bottom of the overhang 16. A helical spring 51 surrounding the bar 18 and in compression between the bearing 49 and a collar 52 tends to urge the presser foot 53 at the lower end of said bar yielding toward the work supporting plate 13. The presser bar 18 is held against rotation through engagement of a lateral projection 54 on a collar 55 on said bar with a longitudinal slot in the lower end of a guide member 56 which depends from the needle head 16 and which is secured by a set screw shown at 57 in Fig. II. The presser bar 18 is liftable against the action of the spring 51 by means of a horizontal lever 58 (Figs. II and VII) fulcrumed on a stud 59 at one side of the standard 8, said lever being connected, by means of a short vertical link 60 with a collar 55. The opposite end of the lever 58 is apertured as at 61 for connection by a rod or chain (not shown) with a foot treadle.

The complementary stitch forming mechanism of the machine includes in this instance a looper 62 which cooperates with a needle 63 in the lower end of the bar 17, beneath the work supporting plate 13. As shown the looper 62 is mounted in a holder 64 secured to a pin 65 whereof the opposite ends are pivoted in upstanding bearing ears of a yoked rocker 66. As further shown the rocker 66 is affixed to a rock shaft 67 which extends transversely of the machine and which is journaled in bearings 68, 69 and 70 respectively set into the side wall 3 and the side walls of the forward offset 7 of the chamber 26 within the machine base 1. The looper 62 receives loop taking and loop shedding motions in a direction

transversely to that of feeding shown by the arrows in Figs. II and IV, as a consequence of oscillation of the shaft 67 induced through an arm 71, and a coupling link 72 from an eccentric 5 73 on the drive shaft 29 within the chamber 25. Needle avoiding movements are induced in the looper 62 in the direction of feeding through 10 rocking of the latter about the axis 65, such movement being imparted through a rod 74 which connects the looper holder 64 to another eccentric 75 on the shaft 29.

The function of advancing the work across the plate 13 as indicated by the arrows in Figs. II and IV is vested in a feed dog 76 which is 15 mounted on a carrier bar 77. As shown in Fig. IV, the carrier bar 77 is yoked at its front end to clear the drive shaft 29 within the compartment or subdivision 26 of the base 1, said dog being secured to the upper or overreaching extremity 77a of said yoke. At its rear end, the feed bar 77 has a pivotal connection 78 with the top end of a rocker 79 which is secured to a rock shaft 80 journaled in spaced bearing lugs 81 and 82 on the base 1. A horizontal arm 83 clamped to an outwardly extending stud 84 on the rocker 79 is coupled, by means of a drop link 85, with an eccentrically disposed pin 86 on a crank disk 87 at the front end of the drive shaft 29 exteriorly of the chamber 26. The crank pin 86 is 20 adjustable radially of the disk 87 by a screw shown at 88 in Fig. V, and is securable in adjusted positions by a clamp nut 89 in a well known manner. Through the connections just described, it will be evident that during each 25 rotation of the drive shaft 29, the feed dog 76 will be reciprocated horizontally to perform a feeding movement. The feed dog 76 derives its up and down or lift movements from an eccentric 30 90 on the drive shaft 29 within the compartment 26, the strap 91 of said eccentric being pivoted at 92 to the underreaching extremity 77b of the feed bar, see Fig. IV.

Mounted on the drive shaft 29 within the chamber 25 immediately adjacent the ball bearing 31 is a disk 95 which dips into the lubricant L in the sump at the bottom of the chamber 25. As the drive shaft 29 rotates, oil is carried up by the disk 95 and impinges upon the inner face 35 of the sloping rear wall 9 of the standard 8, some 40 of the oil so elevated being projected forwardly into the head 16 by the deflecting action of said wall to lubricate the bearings for the needle bar 17 and presser bar 18, and the rod 42, while the rest drops onto the bearings for the rods 47 and 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 projection of the standard; a horizontal drive shaft journaled beneath the work support; and a needle bar operating mechanism including a slide bar which is parallel with said needle bar and which is guided for endwise movement on the standard, a bracket with a boss surrounding the slide bar and a lateral projection engaging, with capacity for free lengthwise sliding movement, a member affixed to the needle bar, means for securing the boss of the arm to the slide bar with capacity for rotative adjustment of said arm about said slide bar, and a rotary actuator on the drive shaft for imparting reciprocatory movement to the slide bar.

2. A sewing machine comprising a horizontal work support with a standard rising therefrom and having at its top a lateral projection which over-reaches the work support; a needle bar guided for up and down movement in the lateral projection of the standard; a horizontal drive shaft journaled beneath the work support; and needle bar operating mechanism including a slide bar parallel with said needle bar, connecting means extending crosswise between the needle bar and the slide bar including a pair of components, one secured to the needle bar and the other to the slide bar and telescopically engaged with each other, a crank on the drive shaft, and a pitman connecting the slide bar with the crank.

3. A sewing machine comprising a frame with a hollow base whereof the top constitutes the work support, and a communicating hollow standard rising from the base and terminating at the top in a lateral hollow communicating head which over-reaches the work support, the rear wall of said standard being inclined upwardly and forwardly toward the head; needle actuating mechanism within the head; and means taking oil from a supply in the base and impinging it upon the inner surface of the inclined rear wall of the standard for dispersion within the machine frame and for deflection of some of the dispersed oil laterally into the needle head to lubricate the needle actuating mechanism.

4. A sewing machine according to claim 3, in which the needle actuating mechanism includes a vertical needle bar confined to endwise movement in the head, a parallel bar guided for endwise movement within the standard, horizontally telescoping means connecting the two bars at the top, and means operated from within the base and connected to the lower end of the parallel bar to reciprocate it.

5. A sewing machine according to claim 3, in which the needle actuating mechanism includes a vertical needle bar confined to endwise movement in the head, a parallel bar guided for endwise movement within the standard, horizontally telescoping means connecting the two bars at the 50

top, a drive shaft extending horizontally through the base, and a pitman connecting a rotary actuator on the shaft with the lower end of the parallel bar to reciprocate it.

5 6. A sewing machine according to claim 3,
wherein the base is subdivided into a compartment which contains the lubricating oil and an auxiliary compartment; and further comprising a rotary shaft which extends through both compartments; a feeding element externally of both compartments; and means partly external to the auxiliary compartment and partly within it by which the feeding element is operated from the drive shaft.

10

15 7. A sewing machine according to claim 3, wherein the base is subdivided by a partition into a compartment which contains the lubricating oil, and an auxiliary compartment through both of which compartments a rotary shaft extends; 20 and further comprising a looper within the auxiliary compartment; and connections including a rock shaft which extends through the partition whereby the looper is actuated by means on the rotary shaft within the lubricant compartment.

25 8. A sewing machine comprising a hollow base with a transverse partition setting apart a chamber which contains a lubricant and an auxiliary chamber, said partition having an offset longitudinally of the base forming an extension of the lubricant compartment; a horizontal rotary shaft extending through both compartments; a transverse rock shaft journalled in and extending from within the lubricant compartment through one of the walls of the offset into the auxiliary compartment; a looper within the auxiliary compartment operated from the rock shaft; and means within the lubricant compartment whereby the rock shaft is actuated from the rotary shaft.

35

9. A sewing machine comprising a hollow base with a transverse partition setting apart a chamber which contains a lubricant and an auxiliary chamber, said partition having an offset longitudinally of the base forming an extension of the lubricant compartment; a horizontal rotary shaft extending through both compartments; a trans-

45 a transverse rock shaft journalled in and extending from within the lubricant compartment through one of the walls of the offset into the auxiliary compartment; a looper within the auxiliary compartment; a bracket arm on the rock shaft within the auxiliary compartment on which the looper is pivoted for swinging movement; a rotary actuator on the rotary shaft within the auxiliary compartment through which the looper is swung as aforesaid; an arm on the rock shaft within the lubricant compartment; a rotary actuator on the rotary shaft within the lubricant compartment by which the last mentioned arm is actuated to oscillate the rock shaft.
